(57) **CLAIM**

The ornamental design for a cloth retainer, as shown and described.

DESCRIPTION

FIG. 1 is a front perspective view a cloth retainer according to the present invention;

FIG. 2 is front elevational view of the cloth retainer of FIG. 1;

FIG. 3 is a rear elevational view the cloth retainer of FIG. 1;

FIG. 4 is a right-side elevational view of the cloth retainer of FIG. 1;

FIG. 5 is a left-side elevational view of the cloth retainer of FIG. 1;

FIG. 6 is a top view of the cloth retainer of FIG. 1; and,

FIG. 7 is a bottom view of the cloth retainer of FIGS. 1.

The broken lines depicting portions of the cloth retainer in FIGS. 1, 3, 4 and 5 are for the purpose of illustrating portions of the cloth retainer and form no part of the claimed design.
